Primary Examiner — Susan E Krakower*(74) Attorney, Agent, or Firm* — Nixon Peabody LLP**(57) CLAIM**

I claim the ornamental design for a display, as shown and described.

DESCRIPTION

FIG. 1 is a perspective view of a first embodiment of a display showing my new design; and,

FIG. 2 is a perspective view of a second embodiment of a display showing my new design.

The broken lines showing the back surface illustrate portions of the display that form no part of the claimed design.

1 Claim, 2 Drawing Sheets**FIG. 1**

FIG. 2
